UNITED STATES PATENT OFFICE.

CHRIST F. DOTTS, OF MILLVALE, PENNSYLVANIA, ASSIGNOR OF ONE-THIRD TO DAVID MOORE, OF PITTSBURGH, PENNSYLVANIA.

LOCKING DEVICE.

1,407,326.

Specification of Letters Patent.

Patented Feb. 21, 1922.

Application filed March 5, 1921. Serial No. 450,008.

To all whom it may concern:

Be it known that I, CHRIST F. DOTTS, a citizen of the United States, residing at Millvale, in the county of Allegheny and State 5 of Pennsylvania, have invented new and useful Improvements in Locking Devices, of which the following is a specification.

This invention relates to locking devices, and more particularly to a locking device 10 specially adapted for use in connection with wire line clamps such as used in well drilling operations.

One of the main objects of the invention is to provide a locking device of simple construction and operation which may be readily applied. A further object is to provide a locking device which will permit ready manipulation of the clamp and will do away with the necessity of moving the T-screw 20 with the left member of the clamp when opened and closed. Further objects will appear from the detailed description.

In the drawings:

Figure 1 is a top plan view of the locking device as applied.

Figure 2 is a side view, the T screw being sectioned, taken substantially on line 2—2 of Figure 1.

Figure 3 is a side view taken from the opposite side to Figure 2.

Figure 4 is a detail front view of the locking nut.

Figure 5 is a detail of the clevis.

The locking device is intended to be used 35 in connection with a wire line clamp such as that disclosed in my U. S. application #379-619 filed May 7, 1920. The clamp comprises two segmental gripping members or jaws 1 and 2. Jaw 2 is provided adjacent to its upper end with an arcuate arm 3 which encircles the upper portion of jaw 1, and jaw 2 is provided at its lower end with a similar arm 4 which encircles the lower portion of jaw 2. Each of the jaws is provided at its 45 upper end with a heavy hook 5 adapted to be inserted through links for suspending the clamp from a temper bar in the known manner. Each jaw is provided in its inner face with an arcuate recess which receives a liner 6 for gripping a cable. Jaw 1 is provided with a forwardly extending integral arm 7 reinforced at its upper and lower edges by flanges 8 which extend about the forward portion of the jaw to form stop elements fit-

ting between arms 3 and 4 so as to positively 55 prevent relative vertical movement between the jaws when assembled. A similar arm 9 projects from jaw 2 and is provided at its upper and lower edges with reinforcing flanges 10 which converge into jaw 2. This 60 provides a clamp of simple and efficient construction in which great pressure may be exerted for gripping the wire line, and the gripping jaws are positively secured against relative vertical movement.

A clip 11 is secured on the outer face of arm 7, which is generally termed the left arm of the clamp. This clip engages about a bight portion 12^a of a U-shaped clevis 12 which straddles arm 7 and is provided at 70 the center of bight portion 12^a with an angularly disposed gripping element or handle 14 which projects through a slot 11^a in clip 11. A U-bracket 15 is secured on the outer face of arm 9 and slidably receives a 75 nut 16 through which is threaded the shank 17 of a T-screw 18, the inner end of this screw being seated at 19 in a recess in arm 9. The screw is secured against outward movement through the bracket by a collar 20 which is threaded upon shank 17 and bears 80 against the inner face of bight 21 of bracket 15, this collar being secured against turning upon the screw by a cotter pin 22 inserted through the collar and the shank of the screw, or in any other suitable or preferred manner. Nut 16 projects above and below 85 bracket 15 and is provided in its forward face with two transversely extending grooves 23 which are adapted to receive the 90 end portions of arms 12^b of clevis 12. Each of these arms is provided at its outer or free end with a knob 12^c connected to the arm by a tapered or beveled element 12^d which is adapted to fit into a corresponding recess or 95 seat 23^a provided at the outer end of groove 23.

In applying the clamp to a line, by grasping T screw 18 and handle 14 the two arms 7 and 9 may be moved toward each other so 100 as to close the clamp upon the line. When the clamp is closed upon the line, the operator swings the clevis by means of handle 14 into substantially the position illustrated in Figure 1 causing the arms of the clevis to 105 engage into the grooves in the nut, this operation being practically automatic and resulting from stoppage of movement of the

arms toward each other when the jaws of the clamp grip the line. After the clamp has been closed the T screw is turned so as to force nut 16 outwardly in bracket 15 thus exerting great pressure upon the cable or line so as to effectively grip the same. This effectively locks the clamp closed, and all possibility of accidental opening of the clamp is eliminated by seating of knobs 12^b in the recesses or seats 23^a at the outer ends of grooves 23 of nut 16. By providing these recesses and the knobs at the ends of the arms of the clevis I permit a slight rocking movement of the knobs so as to insure proper aligning of the clevis thus obtaining accuracy of operation while effectually eliminating all possibility of accidental opening of the locking device. By providing a locking device one part of which is mounted on one arm of the clamp and the other part on the other arm, manipulation of the clamp is greatly facilitated, and it is possible for a single operator to readily close the clamp and secure it upon the cable or line thus avoiding all necessity of one operator holding the clamp in position about the line while another operator closes the clamp and adjusts the locking device, such as is the common practice in locking devices for wire line clamps at present in use.

It may be found desirable in practice to resort to changes in construction and arrangement of the details of the invention without departing from the field and scope of the same, and I intend to include all such variations, as fall within the scope of the appended claims, in this application in which the preferred form only of my invention is disclosed.

40. What I claim is:—

1. In combination with a clamp including arms movable toward and away from each other, a locking member mounted upon one of said arms, a locking member mounted on the other arm, means for detachably securing said locking members together, and means for forcing one of the locking members away from the arm on which it is mounted.
45. 2. In combination with a wire line clamp including clamping members and arms projecting from said members, a locking member mounted upon one of said arms, a locking member mounted on the other arm, means for detachably securing said locking members together, and means for forcing one of the locking members in a direction to close the clamping members.
55. 3. In combination with a wire line clamp including clamping members and arms projecting from said members, a locking member mounted on one of said arms, a locking member mounted on the other arm and movable into and out of engagement with the first mentioned locking member, means for
60. 4. In combination with a clamp including oppositely movable arms, a locking member mounted on one of the arms, means for adjusting said locking member toward and away from said arm, a locking member mounted on the other arm and movable into and out of engagement with the first mentioned locking member, and means for securing said locking members together.
70. 5. In combination with a clamp including oppositely movable arms, a locking member carried by one of said arms and adjustable toward and away from the same, means for adjusting said member, and a locking member mounted on the other arm and movable into and out of engagement with the first mentioned member, said members being provided with co-operating means for preventing separation of the locking members when the first mentioned member is adjusted in one direction.
75. 6. In combination with a clamp including oppositely movable arms, a locking member carried by one of said arms and adjustable toward and away from the same, a locking member rockably mounted on the other arm so as to be turned into or out of engagement with the first mentioned locking member, said first mentioned member being adapted for reception of the second mentioned member, and means for preventing movement of said second mentioned member through the first mentioned member when the latter is adjusted in a direction to close the clamp.
80. 7. In combination with a wire line clamp including clamping members and arms projecting from the same, a clevis mounted upon and straddling one of said arms, and a member mounted upon the other arm and adjustable toward and away from the same, said member being adapted to receive the ends of the arms of the clevis, and the member and the clevis arms being provided with co-operating means for preventing longitudinal movement of the arms of the clevis through said member in the direction of the arm on which the clevis is mounted.
85. 8. In combination with a wire line clamp including clamping members and arms projecting from the same, a clevis mounted at its bight portion on one of said arms and straddling the same, a nut mounted on the other arm and provided with grooves adapted for reception of the end portions of the clevis, and means for adjusting said nut toward and away from said other arm, the nut and the arms of the clevis being provided with co-operating means for preventing movement of the clevis arms through the nut toward the arm on which the clevis is mounted.
90. 9. In combination with a wire line clamp

securing said locking members together, and means for forcing one of said members in a direction to close said clamping members.

75. 4. In combination with a clamp including oppositely movable arms, a locking member mounted on one of the arms, means for adjusting said locking member toward and away from said arm, a locking member mounted on the other arm and movable into and out of engagement with the first mentioned locking member, and means for securing said locking members together.

80. 5. In combination with a clamp including oppositely movable arms, a locking member carried by one of said arms and adjustable toward and away from the same, means for adjusting said member, and a locking member mounted on the other arm and movable into and out of engagement with the first mentioned member, said members being provided with co-operating means for preventing separation of the locking members when the first mentioned member is adjusted in one direction.

85. 6. In combination with a clamp including oppositely movable arms, a locking member carried by one of said arms and adjustable toward and away from the same, a locking member rockably mounted on the other arm so as to be turned into or out of engagement with the first mentioned locking member, said first mentioned member being adapted for reception of the second mentioned member, and means for preventing movement of said second mentioned member through the first mentioned member when the latter is adjusted in a direction to close the clamp.

90. 7. In combination with a wire line clamp including clamping members and arms projecting from the same, a clevis mounted upon and straddling one of said arms, and a member mounted upon the other arm and adjustable toward and away from the same, said member being adapted to receive the ends of the arms of the clevis, and the member and the clevis arms being provided with co-operating means for preventing longitudinal movement of the arms of the clevis through said member in the direction of the arm on which the clevis is mounted.

95. 8. In combination with a wire line clamp including clamping members and arms projecting from the same, a clevis mounted at its bight portion on one of said arms and straddling the same, a nut mounted on the other arm and provided with grooves adapted for reception of the end portions of the clevis, and means for adjusting said nut toward and away from said other arm, the nut and the arms of the clevis being provided with co-operating means for preventing movement of the clevis arms through the nut toward the arm on which the clevis is mounted.

100. 9. In combination with a wire line clamp

- including clamping members and arms projecting from the same, a clevis mounted at its bight portion on one of said arms and straddling the same, a nut mounted on the 5 other arm and provided with grooves adapted for reception of the end portions of the clevis, and means for adjusting said nut toward and away from said other arm, the nut and the arms of the clevis being provided with co-operating means for preventing movement of the clevis arms through the nut toward the arm on which the clevis is mounted while permitting rocking movement of the arms of the clevis in said nut.
- 10 15. 10. In combination with a wire line clamp including clamping members and arms projecting from the same, a substantially U shaped clevis rockably mounted at its bight portion on one of said arms and straddling 20 the same, said clevis being provided at the free ends of its arms with enlarged elements, a nut slidably supported on the other arm for movement toward and away from the same, and means for adjusting said nut, 25 the nut being provided adjacent to its upper and lower ends with grooves adapted for reception of the end portions of the arms of said clevis.
11. In combination with a wire line clamp 30 including clamping elements and arms projecting from the same, a substantially U shaped clevis rockably mounted at its bight portion on one of said arms and straddling the same, a bracket secured on the other arm, 35 a nut slidably mounted in said bracket for movement toward and away from said other arm and projecting above and below the bracket, said nut being provided in its forward face with transversely extending grooves adapted for reception of the end 40 portions of the arms of the clevis, the clevis being provided at the outer end of each of its arms with enlarged elements, and means for adjusting said nut.
12. In combination with a wire line clamp 45 including clamping members and arms projecting from the same, a substantially U shaped clevis rockably mounted at its bight portion on one of said arms and straddling the same, said clevis being provided at its 50 bight portion with an outwardly projecting angularly disposed handle, a bracket secured on the other arm, a nut slidable in the bracket for adjustment toward and away from said other arm, said nut projecting above and below the bracket and being provided in its forward face with transversely extending grooves adapted for reception of the end 55 portions of the arms of the clevis, the clevis being provided at the outer end of each of its arms with an enlarged knob and an inwardly beveled element connecting the knob and the arm and the nut being provided at the outer end of each of said grooves with a seat for reception of said beveled element, 60 and a T screw threaded through said nut and having the inner end of its shank bearing against the arm on which the bracket is mounted, said T screw being secured against outward movement through the 65 bracket.
- In testimony whereof I affix my signature.
- CHRIST F. DOTT.
